UNITED STATES PATENT OFFICE.

WILLIAM W. KARRO, OF GREAT NECK, NEW YORK.

SKATE.

1,393,024.

Specification of Letters Patent. Patented Oct. 11, 1921.

Application filed May 4, 1920. Serial No. 378,888.

To all whom it may concern:

Be it known that I, WILLIAM W. KARRO, a citizen of the United States, residing at Great Neck, Long Island, in the county of 5 Nassau and State of New York, have invented new and useful Improvements in Skates, of which the following is a specification.

This invention relates to improvements in 10 skates.

One of the objects of the present invention is the provision of means for quickly and securely holding the skate in position, the said means providing a securing and comfortable engagement with the shoe of the skater and being removable from the skate so as to permit of the adjustment of the latter to shoes of different sizes by the substitution of different skating means.

Another object is the provision of means 20 for quickly and securely adjusting the skate to fit the shoe, the said means permitting of the removal and attachment of the skate without disturbing the adjustment.

Another object is the provision of a roller 25 skate in which a cushioning or shock absorbing means is interposed between the rollers or roller and the body of the skate.

Other objects and advantages of the invention will appear as the following description is read in connection with the accompanying drawings.

In the drawings:—

Figure 1 is a side elevation of a skate constructed in accordance with the invention.

Fig. 2 is a bottom plan view of the same.

Fig. 3 is a central longitudinal sectional view.

Fig. 4 is a transverse section taken through 40 the stirrup.

Fig. 5 is a detailed perspective view of the stirrup removed from the skate.

Fig. 6 is a transverse vertical sectional view taken on the line 6—6 of Fig. 1.

Fig. 7 is a detail elevation of one of the 45 guide forming members.

Fig. 8 is a detailed elevation of the U-shaped roller carrying frame.

Referring to the drawings in detail, where- 50 in like characters of reference denote corre- sponding parts, the skate to which the im- provements are applied comprises a heel plate 10 and a toe plate 11 these plates being engaged with one another in the usual man- ner, in that they are each formed with longi- tudinally slotted extremities, the slotted ex-

tremity of the heel plate passing through a transverse slot in the toe plate to provide for adjusting the length of the skate to fit 60 shoes of different sizes.

For the purpose of holding the heel plate 10 and toe plate 11 in proper adjusted position, there is provided a rod 12 whose inner end is secured to an enlarged head 13 of a threaded stud 14, the said stud passing 65 through the slot of the toe plate and through an opening provided in the heel plate, being secured in position by a nut 14'. This not only serves to secure the end of the rod 12 in position but serves to connect the plates 70 10 and 11 in a manner to permit of relative sliding movement. The outer end of the rod 12 is threaded as indicated at 15 and this threaded end passes through an opening pro- 75 vided in a lug 16 which is secured to the bottom of the toe plate 11, the size of the opening in the lug 16 being such as to permit of free sliding movement of the rod 12 in the longitudinal adjustment of the skate. Mounted upon the threaded end of the rod 80 12 is an adjustable stop which is shown in the form of a nut 17, so that after the skate has been adjusted to the shoe the end may be positioned against the lug 16 to prevent out- 85 ward movement.

One of the novel features of the invention resides in the provision of means for securing the skate to the shoe so as to permit of the use of the skate in connection with shoes of different sizes and to permit of its quick 90 and secure adjustment to position. For this purpose there is provided a toe stirrup 18 which comprises a metallic plate 19 which is disposed transversely of the toe plate 11 and has its ends connected by a relatively 95 wide flexible member or strap 20, preferably formed of leather. The stirrup is shaped to conform to the shape of the toe of the shoe and is adapted for detachable engagement with the skate and for this purpose is pro- 100 vided with a plurality of key hole slots 21 which engage over headed studs 22 secured to the toe plate 11 so that the stirrup may be removed by a rearward sliding movement and a stirrup of different sizes attached 105 when desired. Any desired means may be employed for securing the heel portion of the skate to the shoe, the one shown comprising a heel receiving member 23 whose side walls are provided with slots for engagement 110 with hooks 25 which are carried by buckles 26, the latter having adjustable engagement

with straps 27. The free ends of these straps may be connected by a clasp 28 or other suitable connection.

While all of the foregoing described features are shown in connection with a roller skate, it is of course obvious that they are quickly adapted for use in connection with ice skates or skates of various types.

Another novel feature of the invention resides in the provision of cushioning means interposed between the rollers and body portion of the skate. The skate shown is of the type in which a single roller is employed at the toe and a single roller at the heel, although a pair of rollers may be substituted at each point if desired. The rollers shown comprise a hub portion 29 through which extends an axle 30. The hub portion 29 is surrounded by a rim in which is secured a rubber tire 31, this being one of the many forms of rollers or wheels which may be used in connection with the skate. These rollers are carried by front and rear trucks 32 and 33 respectively, the latter embodying a substantially U shaped frame 34 whose arms are slotted as shown at 35 for the reception of the rear axle 30. This U shaped frame 34 is mounted for sliding movement in a guide which is formed of spaced side members 36, the edges of which are provided with flanges 37, the arms of the U shaped frame 34 sliding between these flanges. The frame 34 is yieldingly held against movement with respect to the skate and for this purpose there is provided a curved spring 38 having one end secured upon the stud which secures the rod 12 in position with its opposite free end contacting with the under side of the heel plate 10, while the intermediate downwardly curved portion is riveted or otherwise secured to the cross bar of the U shaped frame 34 as indicated at 29.

The front truck 32 is shown as being rigidly secured to the toe plate 11, but if desired a truck similar to the truck 33 may be substituted.

Secured to the heel of the skate and extending rearwardly beyond the rear roller 31 is an outwardly and downwardly curved plate 40 which provides a mud guard and prevents mud and water from being thrown upward by the rear roller by centrifugal force.

The invention is susceptible of various changes in its form, proportions and minor details of construction and the right is herein reserved to make such changes as properly fall within the scope of the appended claims.

Having described the invention what is claimed is:—

1. The combination with a skate, of a toe stirrup carried thereby, said stirrup comprising a plate positioned transversely of the 65 skate, a flexible member connecting the ends of the plate to provide a toe receiving loop, headed studs carried by the skate for detachable engagement with key hole slots formed in the plate of the stirrup to detach- 70 ably connect the same with the skate.

2. The combination with a roller skate, of means for slidably mounting the rollers in a manner to permit of vertical movement of the 75 skate relatively to the rollers, said means comprising a U shaped roller carrying frame, a guide secured to the skate to slidably receive the roller and a spring having one end secured to the skate and the opposite end secured to the U shaped frame to yieldingly hold the latter against sliding movement. 80

3. The combination with a roller skate, of means for slidably mounting the rollers upon the 85 skate, said means comprising a U shaped roller carrying frame, a guide secured to the skate to slidably receive the roller and a spring having one end secured to the skate and the opposite end secured to the U shaped frame to yieldingly hold the latter against sliding movement. 90

4. The combination with a skate including separate heel and toe plates, of a rod having one end connected to the heel plate, said rod having a right angularly disposed pin extending through an opening in the heel plate and means for securing the pin in position, whereby the rod may have a horizontal pivotal movement and means for securing the opposite end of the rod to the toe plate. 100

5. The combination with a skate including separate heel and toe plates, a rod having one end connected to the heel plate in a manner to permit of horizontal pivotal movement, a lug carried by the toe plate and having an opening for the passage of the opposite end of the rod and an adjustable stop mounted upon the last mentioned end of said rod to limit the relative longitudinal movement of the heel and toe plates. 105

6. The combination with a roller skate, of means slidably securing the rollers to the 110 skate, said means including a truck formed of transversely spaced channelled members, means for slidably mounting the rollers between said members and means for yieldingly holding the rollers against sliding movement.

In testimony whereof I affix my signature.
WILLIAM W. KARRO.
